US0D1102225S

(12) **United States Design Patent** (10) **Patent No.:** **US D1,102,225 S**
(45) **Date of Patent:** **** Nov. 18, 2025**

(54) **COMBINED CAP AND CARABINER**

- (71) Applicant: **Nuataaq Holdings, LLC**, Croton on Hudson, NY (US)
- (72) Inventor: **Daniel Ballou**, Long Beach, CA (US)
- (73) Assignee: **NUATAAQ HOLDINGS, LLC**, Croton on Hudson, NY (US)
- (**) Term: **15 Years**
- (21) Appl. No.: **29/988,346**
- (22) Filed: **Jan. 31, 2025**

Related U.S. Application Data

- (63) Continuation-in-part of application No. PCT/US2024/025686, filed on Apr. 22, 2024, and a continuation-in-part of application No. 29/876,566, filed on May 24, 2023, now Pat. No. Des. 1,084,768, and a continuation-in-part of application No. 18/303,906, filed on Apr. 20, 2023, now Pat. No. 12,404,081.

(57) **CLAIM**

The ornamental design for a combined cap and carabiner as shown and described.

DESCRIPTION

FIG. 1 is a first top perspective view of a combined cap and container, showing my new design; FIG. 2 is a second top perspective view thereof; FIG. 3 is a first bottom perspective view thereof; FIG. 4 is a second bottom perspective view thereof; FIG. 5 is a front elevational view thereof; FIG. 6 is a rear elevational view thereof; FIG. 7 is a left side elevational view thereof; FIG. 8 is a right side elevational view thereof; FIG. 9 is a top view thereof; and, FIG. 10 is a bottom view thereof.

(Continued)

Portions of the design that are depicted in broken lines form no part of the claimed design.

1 Claim, 10 Drawing Sheets
